DESIGN FOR A RANGE SURFACE HEATING UNIT

Francis H. McCormick, Dayton, Ohio, assignor to
General Motors Corporation, Dayton, Ohio, a
corporation of Delaware

Application August 26, 1941, Serial No. 103,035

Term of patent 14 years

To all whom it may concern:

Be it known that I, Francis H. McCormick, a citizen of the United States, residing at Dayton, in the county of Montgomery and State of Ohio, have invented a new, original, and ornamental design for a Range Surface Heating Unit, of which the following is a specification, reference being had to the accompanying drawing, forming part thereof.

In the drawing:

Fig. 1 is a top view of a range surface heating unit, showing my new design;

Fig. 2 is a side elevational view of the same; and

Fig. 3 is a sectional view thereof, taken along the line 3—3 of Fig. 1.

I claim:

The ornamental design for a range surface heating unit, as shown.

FRANCIS H. McCORMICK.
